United States Patent Office

Des. 177,030
Patented Mar. 6, 1956

177,030

DINNER PLATE OR SIMILAR ARTICLE

Richard H. Garvin, Syracuse, N. Y., assignor to Onondaga
Pottery Company, Syracuse, N. Y., a corporation of
New York

Application June 24, 1955, Serial No. 36,667

Term of patent 14 years

(CL. D44—15)

The drawing is a plan view of a plate of conventional configuration showing my new design.

I claim:

The ornamental design for a dinner plate or similar article, as shown and described.
